CLAIM

The ornamental design for a display screen with a graphical user interface, as shown and described.

DESCRIPTION

FIG. 1 is a front view of a display screen with graphical user interface according to our new design, the view showing a first image in a sequence thereof;

FIG. 2 is a front view of a second image in the sequence thereof;

FIG. 3 is a front view of a third image in the sequence thereof; and

FIG. 4 is a front view of a fourth image in the sequence thereof;

FIG. 5 is a front view of a fifth image in the sequence thereof; and,

FIG. 6 is a front view of a sixth image in the sequence thereof.

The outermost broken line illustrating an electronic device forms no part of the claimed design. The outermost solid line illustrating the display screen forms part of the claimed design. The remaining broken lines illustrating portions of the graphical user interface form no part of the claimed design.

The appearance of the graphical user interface sequentially transitions between the sets of images shown in FIGS. 1-6. The process or period in which one image transitions to another forms no part of the claimed design.

1 Claim, 6 Drawing Sheets
